UNITED STATES PATENT OFFICE.

AUGUSTUS M. HAMER, OF GOOSE CREEK, TEXAS.

BACKUP POST.

Application filed June 20, 1921. Serial No. 478,944.

To all whom it may concern:

Be it known that I, AUGUSTUS M. HAMER, a citizen of the United States, residing at Goose Creek, in the county of Harris and 5 State of Texas, have invented certain new and useful Improvements in Backup Posts, of which the following is a specification.

This invention relates to new and useful improvements in a backup post for rotaries.

10 One object of the invention is to provide a backup post designed to be carried by a rotary table and to engage with a pipe tong to rotate the same for the purpose of screwing together and unscrewing joints of pipe 15 to which the tong is applied.

Another object is to provide a backup post which will hold the tong at any desired point of adjustment above the table.

With the above and other objects in view 20 the invention has particular relation to certain novel features of construction, operation and arrangement of parts, an example of which is given in this specification and illustrated in the accompanying drawings, 25 wherein:—

Figure 1 is a plan view of a rotary, showing the post thereon.

Fig. 2 is a side view thereof.

Fig. 3 shows a top view of the post, and 30 Figs. 4 and 5 show side views, taken at right angles to each other.

Referring to the drawings the numeral 1 is the rotary table, which is mounted for rotation on the base 2 and which is adapted to 35 engage with and rotate the drill stem or pipe 3.

The numeral 4 is the backup post whose lower end is round to fit into a suitable socket in the table. The post carries a slidably mounted bracket 5, which may be adjusted up and down on the post as desired. One side of the bracket carries a pivoted latch 6, whose lower end engages in one of the spaced notches 7, in the adjacent side of the post to hold the bracket in fixed position. The other side of the bracket has a bearing 8, forming a holder for the handle of the tong 9. This tong is engaged on a section of the pipe 3, and the other section of the pipe is held against turning by the stationary 50 tong 10, so that when the rotary 1, is turned then it will operate through the tong 9, to screw together, or unscrew, the said joints of pipe.

What I claim is:—

55 In rotary well drilling apparatus, the combination with a post of a tong holder adjustably mounted thereon, and including a bracket slidable on the post and a bearing in which the tong handle is slidable; a latch 60 carried by the bracket, spaced catches on the post with which the latch is adapted to engage to hold the holder at any point of adjustment on the post.

65 In testimony whereof I have signed my name to this specification in the presence of two subscribing witnesses.

AUGUSTUS M. HAMER.

Witnesses:

J. H. JONES,
